UNITED STATES PATENT OFFICE.

DE WANE B. SMITH, OF DEERFIELD, NEW YORK.

DESIGN FOR A SPRAYER-BODY.

SPECIFICATION forming part of Design No. 30,184, dated February 14, 1899.

Application filed January 23, 1899. Serial No. 703,185. Term of patent 7 years.

To all whom it may concern:

Be it known that I, DE WANE B. SMITH, a citizen of the United States, residing at Deerfield, in the county of Oneida and State 5 of New York, have invented and produced a new and original Design for Sprayer-Bodies, of which the following is a specification, reference being had to the accompanying drawings, forming a part thereof.

Figure 1 shows a side elevation of a sprayer-body of my present design. Fig. 2 shows a plan view of the same.

The feature of the design is the form and shape of the sprayer-body and the arrangement of the parts constituting the same as follows: the elongated cylindrical portion 1

and the dependent enlarged cylindrical portion 2, located under one end of the portion 1 and arranged at an angle therewith, substantially as shown.

Having described my invention, what I claim as new, and desire to secure by Letters Patent, is—

The design for a sprayer-body, substantially as herein shown and described.

In witness whereof I have hereunto affixed my signature, in the presence of two witnesses, this 17th day of January, 1899.

DE WANE B. SMITH.
